UNITED STATES PATENT OFFICE.

THOMAS W. JOHNS, OF BROOKLYN, NEW YORK, ASSIGNOR TO INTERTYPE CORPORATION, OF BROOKLYN, NEW YORK, A CORPORATION OF NEW YORK.

TYPOGRAPHICAL MACHINE.

1,290,212.

Specification of Letters Patent.

Patented Jan. 7, 1919.

Application filed April 19, 1916. Serial No. 92,207.

To all whom it may concern:

Be it known that I, THOMAS W. JOHNS, a citizen of the United States, residing at Brooklyn, in the county of Kings and State of New York, have invented new and useful Improvements in Typographical Machines, of which the following is a specification.

My present invention relates to improvements in typographical machines of the linotype class as shown and described in Letters Patent No. 436,532, granted September 16, 1890, to O. Mergenthaler. It pertains particularly to the matrix distributing mechanism of the machine and is an improvement upon that shown in said patent.

In linotype machines as heretofore constructed and as shown in said patent, failure of the second elevator to descend, due to obstructions to the transfer of matrices from this elevator to the distributor, or to other causes, resulted in stopping the machine, but this stopping of the machine occurred after the cam which lifts the second elevator had receded from its coöperating part on the second elevator and with which part the cam normally engages. Starting of the machine in those cases required not only removal of the obstruction, but manual manipulation of different parts of the machine, including lowering of the second elevator gently by hand, and failure to properly manipulate any of such parts of the machine would be likely to result in injury either to the machine or to the operator.

The present invention provides an improved device for automatically stopping the machine at a point in its operation where the second elevator is in coöperative relation with its actuating cam, should there be a failure of transfer of the matrices from the second elevator to the distributor box, and this improved device enables the machine to be restarted directly and with facility when the fault has been remedied, it being unnecessary, according to the present invention, to lower the second elevator by hand or to manipulate other parts of the machine, and there is no opportunity of injury either to the machine or the operator.

To these and other ends the invention consists in certain improvements and combinations and arrangements of parts all as will be hereinafter more fully described, the features of novelty being pointed out particularly in the claims.

In the drawing:—

Figure 1 is a perspective view of a portion of a machine of the linotype class, showing the present invention applied to the distributing mechanism thereof.

Fig. 2 is an end view of the main shaft of the machine, the second elevator, and the automatic stopping devices therefor embodying the present invention, and

Fig. 3 is a rear view of the automatic stopping device as shown in Figs. 1 and 2.

The preferred embodiment of the invention is shown in the accompanying drawing and will be hereinafter described in detail. It is to be understood, however, that the invention is not restricted to the particular construction shown, as equivalent constructions are contemplated and included within the scope of the claims.

In the present instance 1 designates a portion of the main frame of a machine of the linotype class as heretofore constructed and as shown and described in the patent above referred to. 2 designates the main shaft of the machine which receives power from a clutch which is not shown in the present instance but is shown in the patent above mentioned, the clutch shifting fork, 3, however, being shown which is pivoted at 4 and has an arm 5 projecting therefrom.

The main shaft 2 carries the cams and other devices for actuating the various parts of the machine, it including the cam 6 which actuates a second elevator 7. The second elevator in machines of this type serves to lift the line of matrices after a cast has been made therefrom up to the point where the matrices are transferred to the mechanism which distributes these matrices to the various channels of the magazine. This second elevator is shown as pivoted on the axis 8 to permit it to rise and fall at appropriate intervals and it has an arm 9 which carries a roller 10 which roller rides on the cam 6.

The second elevator has a normal tendency to occupy its lower position, by reason of the action of gravity, the roller 10 riding on the cam 6. The second elevator carries a rail 11 which receives the line of matrices when the second elevator is in its lower position, and when the second elevator rises, this rail 11 and matrices suspended therefrom come into alignment with a similar rail 12 arranged at the entrance to the matrix distributing mechanism. The ad-

adjacent ends of the rails 11 and 12 are beveled so that when they are alined for the transfer of the matrices to the rail 12, a diagonal joint 13 is formed between them. 5 When the second elevator has ascended to the point where the matrix supporting rail 11 is alined with the rail 12, a pusher operates to transfer the line of matrices from the rail 11 onto the rail 12. This pusher 10 usually comprises a follower 14 to engage behind the line of matrices, a slide 15 which guides and supports the follower, a link 16 which is connected to the slide, and an arm or lever 17 which is connected to the link 15 and is supported on the machine so as to swing to and fro about the axis 18, it having suitable means on the main shaft 2 for reciprocating it at appropriate times. These parts just described comprise a shifting device 15 for transferring the matrices from the second elevator to the distributor.

Heretofore, in machines of this type, obstruction to the entrance of the matrices into the distributor caused one or more of the 25 matrices to occupy a position where it lapped the rails 11 and 12 or extended across the diagonal joint 13 between these rails, and this prevented descent of the second elevator, although the main shaft continued to 30 revolve to a point where the high portion of the cam 6 receded or disengaged from the roller 10. Heretofore, the machine would be stopped because of the failure of the second elevator to descend, but such stopping 35 of the machine did not take place until after the cam 6 had receded or moved out of contact with the roller 10. In machines as heretofore constructed, it was necessary to provide a safety latch comprising the hooked 40 members 19 and 20, it being necessary to engage this safety latch to hold the second elevator 7; it was then necessary to go to the front of the machine and lock the transfer mechanism; it was necessary next to remove 45 the obstructing matrix or matrices, and thereafter to release the safety latch 19, 20 and finally lower the second elevator gently by hand.

The present invention provides means 50 which is controlled according to the position of the distributor shifting device which transfers the matrices from the second elevator to the distributor, the controlling means of the present invention operating 55 automatically to stop the machine in case of an obstruction such as that just described, at a time which will avoid receding of the cam 6 from the roller 10 which actuates the second elevator, the controlling or stopping 60 device of the present invention also embodying means whereby the machine may be restarted directly and with facility after the obstruction has been removed. As shown, the lever or arm 17 of the matrix shifter is 65 provided with a pin or projection 21 and a

lever 22 is provided, this lever being pivoted at 23 on a portion of the frame of the machine and one arm of the lever is provided with a surface 24 on which the pin or projection rides during the to and fro swing 70 of the shifter arm 17, this surface having outer and inner recesses or depressions 25 and 26, spaced thereon in a manner that will hereinafter appear. The opposite end of the lever 22 is connected by a rod 27 to 75 a pawl 28 having a notch 29 adapted to engage a dog or projection 30 carried by the main shaft 2, when the pawl 28 is in its lower position, the dog clearing the pawl 28 when the latter is elevated. The pawl 28 80 is pivotally connected at 31 to the upper end of a lever 32, the latter being pivoted at 33 on the main frame and its lower end is adapted to bear against the arm 5 of the main clutch shifting fork 3. 85

The surface 24 and the notch 25 are so related to the pin or projection 21 on the shifter arm 17 that when the pin engages either the surface 24 or in the notch or depression 25, the pawl 28 will occupy its 90 lower position and the dog 30 which revolves with the main shaft will engage the notch or shoulder 29 of the pawl, pushing the latter longitudinally in the direction indicated by the arrow in Fig. 1 and rocking 95 the lever 32, the lower end of this lever operating upon the arm 5 of the clutch shifting fork 3, and the latter operating to disengage the main driving clutch of the machine. The position of the pin 21 on the 100 shifter arm 17 is such that it will engage the surface 24 or the notch or depression 25 when the follower 14 occupies a position where all the matrices have not been transferred from the rail 11 onto the rail 12. 105 This would occur in case the entrance of the matrices into the distributor were obstructed. The step, notch or depression 26 of the lever is so located with respect to the pin 21 that when the pin 21 recedes in this recess or depression, the follower 14 which transfers the matrices from the rail 11 to the rail 12 has completed its stroke and consequently completed the transfer of the 110 matrices. The arrangement of this step, notch or depression 26 is also such that when the pin 21 rests therein, the pawl 28 will be held elevated sufficiently to permit the dog 30 to pass beneath it, without, however, actuating the pawl to disengage the 115 clutch. The dog 30 is so placed on the main shaft 2 with relation to the second elevator cam 6, that the stopping of the machine will occur prior to movement of the cam out of engagement with the roller 120 10. As the cam 6 remains in engagement with the roller 10, the second elevator is supported in its elevated position, and after the obstructing matrices have been removed, it is only necessary to lift the pawl 28 out 125 130

of engagement with the dog 30, the main driving clutch then reengaging by the action of its spring, and the operation of the machine will be resumed.

5 In using an automatic stopping device embodying the present invention, the safety latch 19, 20 is unnecessary, and starting of the machine may be effected entirely from the rear of the machine and without the necessity of manipulating the second elevator 10 manually as heretofore.

Having thus described my invention, what I claim is:—

1. In a line casting machine having a driving clutch, the combination of a distributor for conducting matrices to their respective channels of a magazine, an elevator for conveying matrices to the distributor, means for transferring matrices from said 15 elevator to the distributor, and means controlled by said matrix transferring means for disengaging the clutch.

2. In a machine of the linotype class having a main driving clutch, the combination of a matrix distributor, an elevator for lifting matrices to the distributor, a slide for shifting matrices from said elevator to the distributor, and automatic means controlled 25 by the position of said slide for disengaging the main clutch.

3. In a line casting machine having a main driving clutch, the combination of a matrix distributor, an elevator for lifting matrices from a lower level to the distributor, a cam for lifting said elevator, a shifter 30 for transferring the matrices from the ele-

vator to the distributor, and means controlled automatically by the shifter for disengaging the main driving clutch while the cam holds the elevator in its upper position. 40

4. In a machine of the linotype class having a main driving clutch, a cam driven thereby, a matrix elevator actuated by said cam, and a matrix distributor to receive matrices from the elevator, the combination of a shifter for transferring matrices from the elevator to the distributor, and means controlled according to the position of the shifter for disengaging the main driving clutch while said cam is in coöperative relation with the elevator. 45

5. In a machine of the linotype class having a matrix distributor, an elevator for conveying matrices thereto, a cam for actuating said elevator, and a clutch for driving the same, the combination of a device for transferring matrices from the elevator to the distributor, a dog movable with and positioned in predetermined relation with the cam, and means positioned relatively to 55 said dog by said transferring device according to the position of the latter, said means when engaged by the dog operating to disengage said clutch.

In testimony whereof I have hereunto set my hand in presence of two subscribing witnesses.

THOMAS W. JOHNS.
